(57) **CLAIM**

The ornamental design for a mobile electronics holder, as shown and described.

DESCRIPTION

FIG. 1 is an exploded perspective view of the mobile electronics holder;

FIG. 2 is an exploded front view thereof;

FIG. 3 is an exploded rear view thereof;

FIG. 4 is an exploded left side elevational view thereof;

FIG. 5 is an exploded right side elevational view thereof;

FIG. 6 is a top view of the base portion of the mobile electronics holder shown separately for ease of illustration;

FIG. 7 is a top view of the upper portion of the mobile electronics holder shown separately for ease of illustration;

FIG. 8 is a bottom view of the base portion of the mobile electronics holder shown separately for ease of illustration;

FIG. 9 is a bottom view of the upper portion of the mobile electronics holder shown separately for ease of illustration; and,

FIG. 10 is a perspective view of a mobile electronics holder showing my new design.

The single broken line extending from the base portion of the mobile electronics holder to the upper portion thereof in the exploded views (FIGS. 2-5) is intended to set forth the pathway along which the base portion is exploded from the upper portion of the mobile electronics holder. All other broken lines represent environmental structures which form no part of the claimed design.
